MESSAGE TRANSMISSION

Application filed February 2, 1929. Serial No. 336,994.

This invention relates to message transmission.

It is among the objects of the present invention to provide a system of and an apparatus for the transmission of a plurality of messages simultaneously over a single carrier wave or electrical conductor.

In connection with the present invention, it will be understood that the term "message" is used in its broadest sense and that the invention is not confined to the specific transmission of code messages or other transmission of intelligence in the form of words, but may be used as will be hereafter seen in the transmission of impulses from a piano or other musical instrument.

Another object of the present invention is to provide a message transmission system and apparatus therefor, which utilize in part some of the principles of the present-day television apparatus.

Another object of the present invention is to provide means for effecting an automatic synchronism attachment for scanning discs.

Still another object of the invention is the effecting of improved means for the operation of an automatic typewriting or printing machine, used in conjunction with the present invention or in accordance with the principles thereof.

Numerous other objects and features of the present invention include the improved method and the novel apparatus for carrying out the method.

It will be seen that the apparatus is simple in construction and efficient in operation and is adapted to the demands of economic manufacture.

The foregoing and other objects of the present invention will be apparent from the following specification taken in conjunction with the accompanying drawings, in which

Figure 1 is a diagrammatic illustration of a transmitting apparatus formed in accordance with the present invention;

Fig. 2 is a similar illustration of a receiving apparatus formed in accordance with the present invention;

Fig. 3 is a sectional view illustrating the

signal lamps, the scanning disc, and the photoelectric cell assembly;

Fig. 4 is a front elevation showing the scanning disc and the associated signal lamp housing;

Fig. 5 is a view similar to Fig. 3 of the receiving disc and associated apparatus;

Fig. 6 is a detail illustration of one form of synchronizing apparatus formed in accordance with the present invention;

Fig. 7 is a detail sectional view illustrating the construction of a piano key for use in connection with the present invention;

Fig. 8 is a transverse section illustrating one method of operating a pneumatic piano in accordance with the present invention;

Fig. 9 is a diagrammatic illustration of a modified method of controlling the scanning disc and the associated signal lamps;

Fig. 10 is a detail illustration of a signal recording means formed in accordance with the present invention;

Fig. 11 is a diagrammatic illustration of that portion of my invention which is designed for the operation of an automatic typewriter or printing machine.

Referring more particularly to Fig. 1 of the drawings, the invention is herein diagrammatically illustrated as including a plurality of circuit controlling devices 10, which, for the sake of conventionality, are shown as simple telegraph keys adapted for the transmission of dot-and-dash telegraph code messages. The circuit for each key includes the common source of potential, indicated at 11, each key being arranged to control the energization of one of the electric bulbs 12. Each of the lights 12 is associated through a conductor 13 with the source of potential 11, the circuit to which light is completed through its respective key 10 and is arranged in such manner as to separately control the illumination of the lights 12 by the associated keys 10.

In connection with this portion of the apparatus, it will be understood that the method and apparatus herein disclosed is not confined to this specific manner of controlling the energization of the light source and that, as will be hereinafter described in connection with Fig. 7, other equivalent means for controlling

55

the light source may be utilized. The circuit herein disclosed is purely diagrammatic and thus other circuits and circuit-controlling means may readily be utilized in connection with the invention.

- From the foregoing it will be seen that each of the lights 12 is individually caused to become illuminated in response to the associated key. The lights 12 are arranged to form a bank of lights with which is associated means for intermittently allowing each light of the bank to effect an electrical circuit, the arrangement being substantially similar to certain principles now successfully utilized in connection with television transmission. A specific and preferred embodiment of the bank of lights and the intermittent means referred to, is illustrated in Figs. 3 and 4, and will be hereinafter described in detail.
- For effecting the intermittent projection of light from the lamps 12 to effect a circuit, a scanning disc 15 is provided, preferably provided with a plurality of apertures 16, one of such apertures being provided for each of the lamps 12 and arranged in spiral formation through the disc 15 in such manner that the aperture 16 corresponding with any one lamp 12, is designed to pass before the lamp and to permit the projection of light therethrough once for every complete revolution of the disc 15. The arrangement is such that during the projection of light from any one of the lamps 12 through its corresponding aperture 16 in the disc 15, the projection of light from any of the other lamps is prevented. The disc 15 is adapted for rotation by a suitable motor 17 associated with a source of potential 18 and rheostat 19 for controlling the speed of the motor. In front of the disc 15 there is provided a photoelectric cell 20, upon which light from the lamps 12 projected through their corresponding apertures 16 is directed, and which in the usual manner controls the flow of current through a circuit 21 which is preferably provided with an amplifier 22 and a transmitter 23, by means of which electrical impulses in response to light received by the photoelectric cell are broadcast over a suitable antenna 24. From the foregoing it will be readily seen that as the disc 15 is revolved at a speed considerably greater than the speed of electrical impulses illuminating the lamps 12, for each period of illumination of any lamp 12, the corresponding aperture of the disc 15 will move before the lamp one or more times to effect impulses in the circuit 21 in response to such illumination, the result being that a plurality of images, one from each of the lamps 12, are broken or "chopped" and successively control the circuit 21 at a high rate of succession.

It will be understood in connection with the present invention that the circuit 21 may be part of a wired circuit of telephone or telegraph arrangement, or, if desired, may be

of the Hertzian wave transmission type, as herein illustrated.

Referring more particularly to Fig. 2, the receiving arrangement designed for use in connection with the transmission system above described, includes a receiving circuit which is used in connection with the Hertzian wave form of transmission and a receiving antenna 25, detector 26, and amplifier 27, which are adapted to receive, detect and amplify the Hertzian carrying wave upon which are superimposed the electrical impulses, through the medium of the photoelectric cells and the associated apparatus. The output of the amplifier includes the circuit 28, by means of which a source of illumination, such as a neon tube 29, is energized and illuminated in response to the rapid successive illumination of the lamps 12. It will be understood that in the use of the present invention with wire telegraphy, the circuit 28 is directly associated with the circuit 21, the amplifier, transmitter, detector and the antenna being displaced by suitable wired transmission adjuncts, such as relays or the like.

For segregating the impulses energizing the tube 29 into their component impulses, a receiving scanning disc 30 is provided, in which apertures 31 preferably provided with lenses therein, are arranged in identical conformity with the apertures 16 of the scanning disc 15, the scanning disc 30 being arranged for rotation by an electrical motor 32 energized through a source of potential 33 and controlled by a rheostat. It will be understood that in accordance with the principles of television, the discs 30 and 15 are caused to rotate in an accurately synchronized manner. In view of the fact that this synchronization of the discs is highly important to the successful operation of the system, and, as a matter of fact, to the successful operation of any system using the television principles, means have been herein disclosed for providing for automatic synchronization thereof, the means being more specifically illustrated in Fig. 6 of the drawings, and will be hereinafter described in connection with that figure.

Arranged before the scanning disc 30, a battery of photoelectric cells 35 is provided similar to the battery of lamps 12. One specific arrangement of the relation of the tube 29, disc 30 and cells 35 has been described in connection with Fig. 5 and will be herein discussed in connection therewith. It will be understood, however, that the cells 35 are arranged in substantially the same manner as the lamps 12, the arrangement being such that the illumination of the neon tube 29 is periodically adapted to successively affect the cells 35 in such manner that impulses in response to the periodic projection of light thereon through the lenses 31, will, through the medium of circuits 36, and, if desired, amplifying means 37, operate a relay 38 or

other signal translating apparatus. It will be readily seen from the foregoing that each of the relays 38 is controlled by one specific lamp 12 and that the device 38 will be intermittently operated in accordance with the illumination of the lamp, and that as the interruptions through the medium of the disc 15 are of high speed, a substantially constant message may be imparted from the keys 10 to the relays 38.

From the foregoing it will be seen that the present invention operates primarily on the principles of television, the picture to be transmitted being displaced by the bank of lamps 12, separate intermittent projections of light from which are received by the photoelectric cell which combines the successive intermittent projections of light into a single signal wave which is directed in a suitable manner to the neon tube 29, which by association with the disc 30 and photoelectric cells 35, divides the signals back into their original components, permitting each signal to affect an associated relay, as will be clearly understood to those skilled in the art to which this invention relates.

Referring more particularly to Figs. 3 and 4 of the drawings, as hereinbefore described, there is herein illustrated a specific form of my invention, in which the lamps 12 are enlarged and elongated to provide a tier of horizontally associated elongated lights 12 positioned within a suitable camera casing 40 including a focusing lens 41, and, if desired, a ground glass or other similar screen 42, upon which the various illuminations of the lamps 12 are projected, and before which the scanning disc 15 is adapted to revolve. Adjacent the scanning disc and arranged to direct light projected through any one of the apertures 16 of the disc, a second lens 43 is provided, which concentrates the light admitted through the aperture 16 upon the photoelectric cell 20. Referring more particularly to Fig. 4, one preferred embodiment of the apertures 16 showing their spiral position, is here disclosed. It will be understood from the foregoing, as disclosed in connection with Fig. 1, the intermittent illuminations of the lamps 12 are designed to be combined through the medium of the scanning disc 15, to intermittently energize the photoelectric cell 20.

Referring more particularly to Fig. 5 of the drawings, as hereinbefore described, there is presented a specific structure of the receiving arrangement which includes the tube 29 arranged for illumination in response to the composite signal given by means of the photoelectric cell 20, before which the apertured screen disc 30 is adapted to rotate. On the opposite side of the disc 30, a set of concentrating lenses 45 is provided, which directs the illumination projected through the aperture 31 of the disc 30 upon the bank of the photo-

electric cells 35, which cells are arranged in exact conformity with the arrangement of the lamps 12, the whole being encased in a suitable casing 46 which is designed to prevent interference from an outside source of light, and thus to assist in the accurate directing of the beam from the aperture 31 to the proper photoelectric cell 35. The photoelectric cells 35 are designed for association with the relays 38, as disclosed in connection with Fig. 2 of the present drawings.

For providing accurate synchronism between the movements of the scanning discs 15 and 30, there is provided an improved and novel synchronizing system which will be more clearly illustrated in connection with Fig. 6 of the present drawings, but which has been illustrated as applied in connection with Figs. 1, 2, 5 and 9 of the drawings. In the present system there is provided in the bank of lamps 12, a separate constantly illuminated synchronizing lamp 50, together with a synchronizing aperture (not shown) in the disc 15, which is adapted to intermittently permit the projection of light from the lamp 50 to the photoelectric cell 20, the positioning of the synchronizing aperture of the disc 15 being arranged in spaced relation to the associated apertures of the disc, whereby the light transmitted therethrough will not interfere with the signal light being transmitted from the lamps 12.

From this arrangement it will be readily seen that positive intermittent impulses of constant strength are superimposed upon the circuit 21 in conjunction with and not interfering with the periodic impulses superimposed thereon from the lamps 12.

The receiving disc 30 is also provided with a synchronizing aperture similar to the aperture described in connection with the disc 15, the arrangement being obviously such that the periodic synchronizing signals sent out over the circuit 21 are received by and similarly energize the tube 20 and when the disc 30 is properly synchronized with movements of the disc 15, the synchronizing illumination of the tube 29 will pass directly through the synchronizing aperture of the disc 30.

By specifically referring to Fig. 6 of the drawings, there is provided in conjunction with the scanning disc 30, a pair of spaced photoelectric cells 51 arranged in a circle described by the revolution of the synchronizing aperture of the disc 30. Associated with each of the photoelectric cells 51, amplifiers 52 are provided and their tubes associated with a suitable relay illustrated as including electromagnets 53, and armatures 54, the arrangement being such that when light strikes the photoelectric cell 51 at the right in the drawings, a circuit including a solenoid 55 and conductor 56 is completed and thus the solenoid 55 is energized. Should light strike the photoelectric cell 51 on the

left of the drawing, a similar solenoid 57 rectilinearly placed with respect to the solenoid 55, is energized through the conductor 58, the return circuit for both solenoids including a conductor 59 with which a suitable source of potential 60 is associated.

In conjunction with the solenoids 55 and 56 and operable in response to energization thereof, a valve 61 controlling the movement 10 of a suitably actuated plunger 62, is provided, the arrangement being such that when light strikes the photoelectric cell 51 associated with the solenoid 57, movement of the valve 61 is to the right, thus uncovering a 15 port 63 and driving the plunger 62 to the right. The port 64 is uncovered by the reverse movement of the valve 61, which may be had through energization of the solenoid 55. Associated with the plunger 62 and operable thereby, a piston 65 is provided. For controlling the resistance of the motor 32, for driving the scanning disc 30, the means herein disclosed includes a chamber 66, containing a resistance conducting fluid 67, together with a fixed electrode 68 associated 25 with one side of the motor 32, while the piston 65 is associated with a co-operating electrode 69 associated with the opposite sides of the motor, the arrangement being such that the 30 distance between the electrodes 68 and 69, controls the resistance of the circuit, and as the position of these is controlled through the energization of the photoelectric cells 51, it will be understood that the motor speeds 35 are directly responsive to such energization.

Referring again to the synchronizing aperture of the receiving disc 30, which is disclosed as at 70, as herein described one of the discs 15 and 30 is in proper alignment and 40 properly synchronized, the synchronizing impulses of the tube 29 is given at a time when the synchronizing aperture 70 is directly between the photoelectric cells 51 and that by the time the aperture 70 has reached one or the 45 other of the cells 51, the signal impulse has been completed and thus neither of the photoelectric cells 51 is energized. On the other hand, should the speed of the disc 30 increase or diminish over that of the speed 50 of the disc 15, the aperture 70 will receive the signal impulse when it is in line with one or the other of the photoelectric cells 51, the photoelectric cell to the left in Fig. 6 being energized when the speed of rotation 55 of the disc 30 is increased, and conversely the opposite photoelectric cell being energized when the speed of the disc 30 is below that of the speed of the disc 15. When the aperture 70 registers at the time of the synchronizing impulse with one or the other of the photoelectric cells, the cell is energized and its associated solenoid energized in a manner to cause movement of the plunger 62 and thus vary the resistance in 60 the motor 32 in a manner to rectify the speed

of the motor to conform with the speed of the motor 17. It will be understood that a special "hunting" action takes place in such manner as to maintain the relative speeds of the discs 15 and 30 within the range of divergence permitted by the positioning of the photoelectric cells 51 and that a normal balance of speeds and an effective synchronizing between the discs are provided for.

Referring more particularly to Fig. 7, the 70 keys 10 as illustrated in Fig. 1 of the drawings, are here shown as supplanted by a piano key controlling member including a key 75, adapted to actuate a plunger 76 which moves in a resistance fluid conductor 77, the downward movement of the key 75 increasing the reception of the plunger 76 within the fluid 77, thereby decreasing the resistance in the key circuit, one side of which is associated with the plunger 76 while the other side is 80 associated with the fluid 77. Thus the energization of the lights 12 is both in accordance with and in proportion to the movement of the key 75.

By referring to Fig. 8, the relays 38 of 90 Fig. 2 have been displaced by an electromagnet 78 adapted to operate a valve 79 in the tracker bar of the piano, in a manner to control playing of associated keys.

In connection with Figs. 7 and 8 of the 95 drawings, it will be seen that the arrangement is such that a piano or similar instrument may be effectively operated through the medium of the present invention, and that through the use of the device as illustrated, not only are the specific impulses transmitted to the receiving piano, but in addition the technique of the player is reproduced.

Referring more particularly to Fig. 9 of the drawings in conjunction with Fig. 1, in which the complete transmitting arrangement has been illustrated, there is here provided an improved means by which the intermittent successive projection is stepped up. In this instance the disc 15 is provided with a plurality of apertures for each of the lamps 12, and a circuit controller including a number of sectors in conformity with the number of apertures provided for each of the lamps 12, is associated with the motor 17 and operable thereby. The lamps 12 are divided into groups "A" and "B", as illustrated, the ground wire for each group being associated as by a conductor 80, with its particular sector of the circuit controller 81. In illustrating the operation of the device, such illustration is simplified by considering the use of a four-sector circuit controller and four groups of the lamps 12, together with four apertures for each one of the lamps in the scanning disc 15. The arrangement is such that as the quadrant of the scanning disk 15, which for instance through the circuit controller 21, passes before these lamps to permit energization of 120 125 130 135 140 145 150 155 160 165 170 175 180

the group A of lamps 12, energization thereof is permitted and such energization is scanned by those apertures in this sector which correspond with these lamps. As the 5 disc moves into the next adjacent quadrant, the next adjacent group of lamps is permitted to be energized through the circuit controller 81, and they are thus scanned during passage of this quadrant there- 10 tween, and so on through the entire rotation of the disc 15.

By the use of the above feature of the present invention, it will readily be seen that an unnecessary use of energy and the unnecessary energization of the lamps 12, are 15 avoided, and thus inaccuracies in the system are prevented. It will also be seen that by the use of this system considerably more of the lamps in a single apparatus may be utilized. Thus a greater number of messages 20 may be sent. It will be understood in this connection that the receiving arrangement is similarly constructed by the provision of a circuit controller, whereby the segregation 25 of the messages is properly effected.

Referring more particularly to Fig. 10 of the drawings, there is here disclosed an apparatus for recording the messages received and segregated by the receiving disc 30, the 30 arrangement including the neon tube or other light source 29, which is controlled by the photoelectric cell 20 and before which passes the scanning disc 30 with its apertures 31. The opposite side of the scanning disc 30 35 is adjacent a concentrating lens 85, which directs the segregated light impulses through a slit 86 in a partition 87 within a cabinet 88 housing the apparatus. Before the slit 86, a plurality of suitable tapes 89 are caused 40 to move through the medium of a suitable motor 90 and associated drum. The tapes 89 are preferably formed of some light sensitive material, the arrangement being such that the intermittent flashes of light controlled by the scanning disc 30 in conjunction 45 with the tube 29, leave their trace upon the tapes 89. It will be understood that a tape is provided for each of the lamps 12 and in place of the photoelectric cell 35. By this apparatus, permanent records of the 50 messages transmitted are received, each tape bearing marks indicating the intermittent energization of the lamps 12. Thus the tapes may be removed from the casing 88 and be 55 translated at leisure. The relays used in connection with the photo-electric cells at the receiving end of the system, should be arranged electrically or mechanically so that their armatures will not be caused to flutter 60 or vibrate between the beginning and the end of a component signal impulse. In this case it is understood that the instrument is arranged according to well-known electrical principles whereby the component impulses 65 of a signal will be maintained long enough

to effect the same result as a single signal.

When only one or two segregated message signals are to be the normal capacity of reception at a receiving station, the small aperture shown in the scanning discs, may be in the form of a long slot, diametrically disposed, thereby allowing a maximum illumination from the neon light to pass through. In this connection also it will be seen that with a few messages as the normal desired capacity, larger cells may be used; it will be further seen also that the photo-electric cells in the receiver may be unconventionally placed, some being further away than others from the disc, instead of in a plane bank as illustrated. 70 This allows larger cells to be used. It will be further obvious that any combination of photo-cells may be used for messages at a station. To obtain the use of large cells in another way than the above, quartz rods may 75 be used to carry the segregated illumination beams to their respective associated apparatus at both the transmitter and receiver, in a well known way.

A number of banks of lights may be used 80 at the transmitter and a corresponding number of banks of photo-electric cells may be used at the receiver, to effect a greater increase in the number of messages possible. Transmission in this way may be carried out 85 by providing a circuit controller to allow only one bank at a time to be in operation.

Messages may be recorded in another way by displacing the relays associated with the photo-electric cells, with a magnetized tape 100 device capable of recording magnetic impulses according to well known practice.

In connection with Fig. 6, it will be seen that the relays themselves may operate the resistance rod 65 direct; or the solenoids may 105 be arranged to operate the piston against a controllable air pressure or pneumatic resistance instead of having a vacuum for this purpose.

It will be obvious that a plurality of segregated simultaneous component signal impulses may be used to transmit one message-character. Although one of the main objects of my invention is the effecting of an apparatus which will transmit a maximum number of messages simultaneously, a large number may still be transmitted simultaneously even if four or five signals are taken for a single character. In connection with this feature, I have devised a mechanism which will enable an automatic printing or typewriting machine to be used effectively upon this principle. This mechanism is depicted in one form in Fig. 11 which is a diagram of the mechanism for the receiving end and shows 110 how the lights are controlled at the transmitter.

Now referring to Fig. 11, 91 is an automatic typewriting machine suitable for use 115 in message transmission. This may be elec- 120

trically operated, the closing of circuits effecting the printing of the keys. Accordingly, I have shown means for properly controlling these circuits. In this case I have shown five photo-electric cells, as this number is adequate for forming enough different combinations for all the keys of an ordinary typewriter. Obviously more can be used where more characters are to be transmitted, for instance in a machine where different types are used such as in newspaper work or typesetting where a system such as the present one, may be used. The photo-electric cells 92, are part of the signal receiving system as set forth in this application, although the present invention is not restricted to this specific arrangement in this connection. Each of these five cells is electrically connected to the primary coil of a relay 93, through a potential in a well known way. The local current of the relay serves to energize a solenoid 94 capable of closing another circuit, by making a contact with a member 95. The closing of this last circuit causes the key combination mechanism of the typewriting machine to be put into such a position that when another circuit 96 is closed the typewriter key will be caused to print, and the key printed will be determined by the specific members of the combination effected. This circuit 96, or printing circuit, is closed when any of the relays 93 is energized by a signal, and inasmuch as the speed at which the five relays are affected will be practically simultaneous, as set forth in my invention, the effecting of the printing circuit 96 will not be accomplished until all the members of the combination control 95 have had ample time to be put into controlling position. The breaking of the relay circuit at the end of a transmitted signal will not only cause the members 95 of the combination mechanism to be put into normal position, but will also cause the printing circuit 96 to be put into normal position, by the breaking of circuit 96. This circuit 96 is broken when the relay armature 98 is in normal position, as the contacts 97 of circuit 96 are then apart. The closing of circuit 96 may be retarded as much as necessary according to the speed of the message transmission segregating system, by arranging suitable electrical means such as resistance wire in the circuit, or by using some form of mechanical retarding means.

It will be obvious in considering the invention that other changes may be made in the invention without detracting from the merit thereof, or the spirit of the invention, particularly in regard to the lights. For instance, instead of utilizing the perforated discs in the invention, with the accompanying mechanism for transmitting and receiving the segregated message signals, it will be seen that revolving contacts may be used, thus

enabling the same results to be obtained but in a somewhat different manner. Such a revolving contact device may be used only at one end if desired, while the perforated disc may be used at the other, as may be deemed best. 70

When a revolving contact is used for lighting signal lights, the advantage is obtained of enabling a stronger signal light to be obtained, as there may be an individual light for each of the segregated signals, these being each as large and strong as the need requires, while with the discs the light would necessarily be much weaker. Although the said revolving contacts may operate the relays direct, I prefer to have the lights regulate the current in photo-electric cells, as it will be found more efficient principally because of the persistence of each signal impulse on a light source. 75

One of the "automatic typewriter" keys at the receiver may be used to actually print any character, instead of having this done automatically when a signal is received as hereinbefore described. This feature is carried out by arranging a separate combination of signals for actuating the mechanism which operates the printing key according to and when the signal combination is received. This method of separately controlling the actual printing mechanism may be further varied by arranging another or sixth segregated signal especially for this purpose. 80

From the foregoing it will be readily seen that a novel and improved method of transmitting a plurality of messages over a single circuit or upon a single carrier wave has been provided and that there has been provided in conjunction therewith a novel and improved synchronized means for use in connection with receiving and transmitting scanning discs of television apparatus or the like. The invention also provides means for the transmission of piano or similar key impulses and also provides for the separate recording of a plurality of simultaneously transmitted messages. 85

It will also be understood in connection with the present invention, that numerous changes and modifications of the structural details and the full use of equivalents may be resorted to without departing from the spirit or scope of the present invention as outlined in the appended claims. 90

What is claimed is:

1. A method of communication which includes the energizing of a plurality of lights by a plurality of associated signal devices, and successively and intermittently superposing light from said lights upon light responsive means to propagate a single signal in response to said intermittent and successive superposings of said lights. 105

2. A communication apparatus, including 110

- a plurality of light sources individually energized by associated signal devices, a photoelectric cell, and means interposed between said cell and said light sources for periodically and successively permitting projection of light from said sources to said photoelectric cell. 3. A communication apparatus, including a bank of individually energized light sources, scanning means for said bank, and a photoelectric cell successively energized by the individual lights of said bank and the transmission of a single signal by said photoelectric cell. 4. A communication apparatus, including a signal device for separately actuating separate light sources in a bank of light sources, television means for combining and subsequently dividing the signals, and photoelectric means for retransmitting separate signal impulses in response to said signal device. 5. A method of communication, which includes the step of simultaneously propagating a plurality of signals, energizing a photoelectric cell by successive portions of said signals, and propagating a signal wave in response to the energization of said cell. 6. A method of communication, which includes the step of simultaneously propagating a plurality of signals, energizing a light source in response to each signal propagated, operating a scanning disc before said lights, energizing a photoelectric cell by light transmitting through said scanning disc, and propagating a single signal in response to the energization of said photoelectric cell. 7. A communication apparatus including a plurality of light sources individually energized by associated signal devices, a photoelectric cell, and a scanning disc interposed between said cell and said light sources for periodically and successively permitting projection of light from said sources to said photoelectric cell. 8. A communication apparatus, including a plurality of light sources individually energized by associated signal devices, a photoelectric cell, a scanning disc interposed between said cell and said light sources for periodically and successively permitting projection of light from said sources to said photoelectric cell, and a signal broadcasting apparatus adapted to broadcast a signal modulated in accordance with the energization of said cell. 9. A communication apparatus, including a plurality of light sources individually energized by associated signal devices, a photoelectric cell, a scanning disc interposed between said cell and said light sources for periodically and successively permitting projection of light from said sources to said photoelectric cell, a signal broadcasting ap-
- paratus adapted to broadcast a signal modulated in accordance with the energization of said cell, and a receiving apparatus including a light source controlled by said broadcast signal and a scanning disc for segregating the component signals from said broadcast signal. 10. 15. 20. 25. 30. 35. 40. 45. 50. 55. 60. 65. 70. 75. 80. 85. 90. 95. 100. 105. 110. 115. 120. 125. 130.
